(57) **CLAIM**

The ornamental design for a storage container for recyclable plastic bags, as shown and described.

DESCRIPTION

FIG. 1 is a front elevational view of a container for recyclable plastic bags, showing our new design;

FIG. 2 is a rear elevational view thereof;

FIG. 3 is a front perspective view thereof;

FIG. 4 is a top plan view thereof; and,

FIG. 5 is a bottom plan view thereof.

The small areas of cross hatching are understood to represent a texture that continues throughout the surfaces.
